Primary Examiner — Ian Simmons*Assistant Examiner* — Shannon Morgan(74) *Attorney, Agent, or Firm* — Lowe Graham Jones PLLC(57) **CLAIM**

The ornamental design for a measuring spoon set, as shown and described.

DESCRIPTION

FIG. 1 is a top perspective view of a measuring spoon set showing our new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a bottom plan view thereof.
